ADDRESS DEVICE.

APPLICATION FILED APR. 21, 1919.

1,376,900.

Patented May 3, 1921.

FIG. 2.

A technical diagram of a rectangular frame, likely a door or window frame, with various numbered components. The frame is shown in perspective, with dashed lines indicating hidden parts. The following components are labeled:

- 22: A label at the top left.
- 18: A label at the top right.
- 21: A label below 18.
- 19: A label on the right side.
- 23: A label on the left side.
- 17: A label on the far left.
- 20: A label at the bottom left.
- 16: A label at the bottom center.
- 11: A label on the far right.

The frame itself is labeled with the number 560.

A technical drawing of a rectangular frame structure. Inside the frame, there is a central rectangular component labeled '18' at the top. Above '18' is the number '21' and above that is the handwritten label 'FIG. 3.' To the right of '18' is a vertical rectangular component labeled '19'. Below '19' is another vertical rectangular component labeled '20'. At the bottom center of the frame is a horizontal rectangular component labeled '16'. To the left of the frame, there is a vertical line labeled '11' with a leader line pointing to the left edge of the frame.

UNITED STATES PATENT OFFICE.

ANDREW TRUST POEHLMANN, OF CATONSVILLE, MARYLAND.

ADDRESS DEVICE.

1,376,900.

Specification of Letters Patent.

Patented May 3, 1921.

Application filed April 21, 1919. Serial No. 291,445.

To all whom it may concern:

Be it known that I, ANDREW TRUST POEHLMANN, a citizen of the United States, residing at Catonsville, in the county of Baltimore and State of Maryland, have invented a new and useful Address Device, of which the following is a specification.

This invention is a device of the type ordinarily attached to shipping receptacles and the like, by means of which the destination of the receptacle and other desirable data may be carried.

One of the objects of the invention is to provide a simple device of the character referred to, capable of being attached to a shipping receptacle by means of which the names of the consignee and of the shipper respectively, may be conveniently displayed and in which the same label may be employed for address purposes when the receptacle is returned to the original shipper. A further object is to provide a reversible label carrier having means by which an address tag may be engaged and retained thereby. A further object is to provide a holder for the label carrier, said holder having eight openings for the indicia attached to the label carrier, and having means coöperating with the carrier by which the latter is retained in position, and accidental removal thereof is prevented.

The invention will be hereinafter set forth and particularly pointed out in the claims.

35 In the accompanying drawings:—

Figure 1 is a perspective view illustrating an address device constructed in accordance with the invention. Fig. 2 is a similar view illustrating the label carrier removed from the holder. Fig. 3 is a back view of the label carrier. Fig. 4 is a longitudinal section view of the entire device illustrated in Fig. 1. Fig. 5 is a horizontal sectional view taken on the line 5—5, Fig. 4.

45 Referring to the drawing, 10 designates a base of any suitable material, preferably of thin sheet metal, provided with means whereby it may be attached to a carrier, the means illustrated consisting of holes 11 for the reception of securing devices. Attached to said base are flanges 12 of a face plate 13 shaped at its edges to provide a space between it and the base 10, whereby a holder is provided having one side and both ends closed, the other side being provided with an opening through which the

label carrier may be inserted. The face plate is provided with eight openings 14, 14', 15 and 15' and suitable indicia may be printed contiguous to said openings. For 60 purposes of illustration the word "From" may be placed above the opening 14 and the word "To" placed above the opening 15. The same words are correspondingly placed contiguous to the openings 14' and 65 15', but it will be noted that the words have been reversed both as to position with relation to the words contiguous to the openings 14 and 15 and also with relation to each other.

70 The label carrier consists of a body 16 of sheet material provided with hook-like flanges 17 on its side edges, and having eight openings 18 and 19 positioned to correspond with the openings 14 and 15 or 75 the openings 14' and 15' of the face plate. Attached in suitable manner to the back of the body 16 is a clip 20 capable of engaging and retaining a card 21 which is provided with the shipper's address indicated at 22 80 and the consignee's address indicated at 23. The flanges 17 serve a twofold purpose, first to provide a means of engagement for the operator's hand in placing the carrier into and removing it from the holder, and 85 second, the innermost flange serves as a means for preventing accidental removal of the label carrier. The holder may be provided with any suitable form of catch to coöperate with the flange 17, but for purposes of illustration the face plate is shown as provided with a slit portion 24 which is slightly depressed to serve as a spring catch 90 capable of engaging the flange 17. It is preferred to slightly depress the strips 25 95 between the eight openings so that they will have a yieldable engagement with the label carrier, and thereby prevent a too free movement thereof.

100 In practice a card 21 is slipped under the clip 20 so that the shipper's address is displayed through the opening 18 and the consignee's address is displayed through the opening 19. The carrier 16 is then inserted into the holder so that the address 22 shows 105 through the opening 14 and the address 23 shows through the opening 15, the carrier being pushed into the holder until the innermost flange 17 is engaged by the catch 24. When the consignee desires to return 110 the receptacle, the carrier 16 is removed by pressing out the outermost flange 17 or

pulling thereon sufficiently to disengage the carrier from the catch 24. After the carrier is withdrawn its position is reversed and it is again inserted into the holder so 5 that the address 22 comes opposite the opening 15' and the address 23 comes opposite the opening 14'. The holder now contains directions by which the receptacle is returned to the original shipper and an indication 10 that it is from the original consignee. Thus the same label serves for both forwarding and return purposes.

Having thus explained the nature of the invention and described an operative manner 15 of constructing and using the same, although without attempting to set forth all of the forms in which it may be made, or all of the forms of its use, what is claimed is:—

- 20 1. An address device of the character described comprising a holder having sight openings contiguous to both ends, locking means carried by said holder, and an address carrier having spaced apart flanges 25 either of which may be engaged with said locking means to prevent accidental removal of said address carrier, the flange distant from that engaged by the locking means being exposed for convenient engagement to withdraw said address carrier from the holder, said address carrier having means for exposing an address through either of the sight openings of the holder.
2. An address device of the character described comprising a holder having sight 35 openings contiguous to both ends, locking means contiguous to one edge of said holder, and an address carrier constructed for slideable engagement with said holder and having its side edges provided with flanges, either of which may be engaged with said

locking means to prevent accidental removal of said address carrier, the flange distant from that engaged by the locking device being extended beyond the contiguous edge of 45 the holder whereby it may be conveniently engaged to withdraw the address carrier from said holder, said address carrier having means for exposing an address through either of the sight openings of the holder. 50

3. An address device of the character described comprising a holder provided with a spring catch, said holder also having sight openings contiguous to both ends, and a reversible address carrier having side edges 55 provided with spaced apart flanges either of which may be interlocked with said catch to prevent accidental removal of said address carrier, the flange distant from that engaged by the catch being exposed, whereby it may be conveniently engaged to withdraw the address carrier from the holder, said address carrier having means for exposing an address through either of the sight openings of the holder. 60

4. An address device of the character described comprising a holder provided with sight openings contiguous to its ends, a reversible carrier also having sight openings and side edges provided with flanges, means 70 for attaching a card to the carrier in a position to come opposite the sight opening thereof, and means carried by the holder capable of interlocking with either flange of the carrier, whereby the sight openings 75 in the carrier are brought into register with the sight openings at either end of the holder.

In testimony whereof I have hereunto set my hand.

ANDREW TRUST POEHLMANN.
